CLAIM

The ornamental design for a compressible bottle, as shown and described.

DESCRIPTION

FIG. 1 is a front elevational view of a compressible bottle showing my new design;

FIG. 2 is a rear elevational view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof; and,

FIG. 8 is a perspective view of shown in a compressed state thereof.

The broken lines in the drawings showing of the compressible bottle illustrate the portions of the compressible bottle that form no part of the claimed design.
